STOPCOCK

Andrew Harautuneian, Gardena, Calif., assignor to
Pharmaseal Laboratories, Glendale, Calif., a corpora-
tion of California

Filed Jan. 29, 1962, Ser. No. 68,558

Term of patent 14 years

(Cl. D16—1)

FIG. 1.

FIG. 2.

FIG. 3.

FIG. 4.

FIG. 5.

FIG. 6.

FIGURE 1 is a top plan view of a stopcock, showing my new design;

FIGURE 2 is a left side elevation thereof;

FIGURE 3 is a front elevation thereof;

FIGURE 4 is a right side elevation thereof;

FIGURE 5 is a bottom plan view thereof; and

FIGURE 6 is a rear elevation thereof.

I claim:

The ornamental design for a stopcock, as shown.
